UNITED STATES PATENT OFFICE.

EDWIN J. CUBLEY, OF RAVENSWOOD, ILLINOIS.

DESIGN FOR A BANJO.

SPECIFICATION forming part of Design No. 19,080, dated May 7, 1889.

Application filed June 8, 1888. Serial No. 276,534. Term of patent 7 years.

To all whom it may concern:

Be it known that I, EDWIN J. CUBLEY, a citizen of the United States, residing at Ravenswood, in the county of Cook and State 5 of Illinois, have invented and produced a new and Original Design for a Banjo, of which the following is a specification, reference being had to the accompanying drawings, forming part thereof.

10 In said drawings, Figure 1 represents in perspective a banjo embodying my design. Fig. 2 is a plan view of the under side of the head of the banjo. Fig. 3 represents two of the brackets detached and respectively in different 15 positions.

The leading feature of my design consists of the outer cylindric surface of the circular hoop of a banjo, provided with a series of 20 projections, E, each of which projections comprises an oblong rectangular body having a cylindric outer face, e', and each of its flat sides perpendicular to the cylindric surface of the hoop.

In said drawings, A indicates the circular

hoop, provided with a series of brackets, E. 25 Each bracket involves an oblong rectangular body portion, e, having a part-cylindric face, e'. The bracket is in width quite narrow as compared with its length, and has its four flat sides projecting from and perpendicular 30 to the outer cylindric surface of the hoop.

The conjunction of the bracket with the hoop gives an exceedingly neat, simple, and graceful appearance to the banjo and avoids all clumsiness, it being seen that the part- 35 cylindric face of the bracket harmonizes with the curvature of the hoop.

I claim—

The design for a banjo herein shown and described, the same comprising the hoop provided with the series of oblong rectangular-shaped brackets, each having the outer cylindric face, e', as set forth. 40

EDWIN J. CUBLEY
